UNITED STATES PATENT OFFICE.

CHARLES H. SMITH, OF COLUMBUS, OHIO.

DESIGN FOR A BADGE.

SPECIFICATION forming part of Design No. 20,969, dated July 28, 1891.

Application filed December 24, 1890. Serial No. 375,737. Term of patent 3½ years.

To all whom it may concern:

Be it known that I, CHARLES H. SMITH, a citizen of the United States, residing at Columbus, in the county of Franklin and State 5 of Ohio, have invented and produced a new and Original Design for Badges, of which the following is a complete specification, reference being had to the accompanying drawing, forming a part thereof.

10 In said drawing, the figure shown represents a face view of my badge, the parts composing the design being so shaded as to show the portions which are in relief, this view being deemed necessary to fully illustrate my 15 design.

15 Heretofore badges have been produced in the form of a disk showing certain raised ornaments or figures thereon, and I therefore confine myself to the ornamentation of said 20 badge.

My design consists, as shown, in a flattened disk-shaped body *a*, having formed centrally on the face thereof the representation in relief of two clasped hands *b*, above and below which are arranged scrolls *c*. These figures are inclosed by a circle *d*, which is surrounded at a distance therefrom by a larger edge circle *e*, formed by the raised face edge 25 of the disk. The circular space between these two circles is adapted as a background 30 for suitable lettering, as indicated. As shown in the drawing, the background is stippled or matted.

What I claim is—

The design for a badge, substantially as 35 herein shown and described.

CHARLES H. SMITH.

In presence of—

BARTON GRIFFITH,
C. C. SHEPHERD.
